ALDEI LANDRY, OF CENTRAL FALLS, RHODE ISLAND, ASSIGNOR TO HEMPHILL COMPANY, OF CENTRAL FALLS, RHODE ISLAND, A CORPORATION OF MASSACHUSETTS.

YARN-FEEDING MECHANISM FOR KNITTING MACHINES.

Application filed August 5, 1919. Serial No. 315,531.

This invention relates to yarn feeding mechanism for knitting machines and more particularly to automatic yarn changing mechanism.

In order that the principle of the invention may best be understood, I have shown merely as examples certain illustrated embodiments which will be hereinafter more fully set forth, while the scope of the invention will 10 be more particularly pointed out in the appended claims.

In the drawings:—

Fig. 1 is a fragmentary rear elevation of a knitting machine showing the yarn guides together with portions of their supporting and actuating instrumentalities;

Fig. 2 is a vertical section taken on the line 2—2 of Fig. 1 through one side of the needle cylinder cam ring and associated parts, the yarn guides and thread operating means being illustrated in connection with said needle cylinder.

Fig. 3 is a detail view on an enlarged scale of one of the yarn guides and its actuating means;

Fig. 4 is a plan view of the latch ring and its support with a plurality of yarn guides mounted thereon;

Fig. 5 is a detail view on an enlarged scale of the yarn guide and operating means illustrated in Fig. 2, said yarn guide being shown in full lines in its yarn feeding position and in dotted lines in its yarn holding or withdrawn position;

Fig. 6 is a detail view of the parts illustrated in Fig. 5 with the latch ring or yarn guide supporting member swung to its inoperative position;

Fig. 7 is a detail view similar to Fig. 5 illustrating a modified form of yarn guide, the yarn guide being shown in full lines in its yarn feeding position and in dotted lines in its retracted position, the latch ring or yarn guide supporting member being also shown in dotted lines in its operative position;

Fig. 8 is a detail view of still another form of yarn guide, the yarn guide supporting member or latch ring being shown in dotted lines in its inoperative position; and

Fig. 9 is a section similar to Fig. 2, illustrating a modified form of yarn guide and yarn guide actuating means.

Referring to the drawings wherein I have

preferably though not essentially, disclosed as a basis for my invention an automatic, circular knitting machine 1 as a needle cylinder herein shown mounted upon a beveled gear 2 arranged to revolve in a suitable recess formed in the bed plate 3 of the machine, said beveled gear being driven by suitable well-known means, not herein shown or described. The needle cylinder 1 is longitudinally grooved to receive independently movable needles 4 which may, in so far as this invention is concerned, be spring or latch needles, the latter being shown, and these needles are operated longitudinally of the grooves in said needle cylinder by the usual knitting cams, indicated at 5 in Fig. 2. During the operation of the knitting machine, the yarn or yarns are led to the needles during the formation of various sections of the work, and it is desirable often to change the character of said yarns in accordance with certain sections of said work, sometimes inserting a number of yarns at the same time while at other times only one yarn may be in use, and the changing of said yarns is usually automatic and effected by means including pattern mechanism.

When latch needles are employed as shown, a latch ring similar to that shown at 6 is essential in order to insure the proper positioning of the latches during the stitch forming operations. It is generally the custom in machines of the type herein shown to mount the yarn guiding means in the latch ring, and herein I have shown a plurality of yarn guides preferably five in number, 90 as indicated at 7 pivotally mounted in said latch ring 6.

In the present example, referring more particularly to Figs. 1 to 6 inclusive, the latch ring 6 is pivotally mounted at 8 in a standard 9 projecting upwardly from the bed plate 3, said standard 9 being forked at its upper end to receive between the arms thereof the fittingly forked end 10 of said latch ring. Mounted between the arms of 100 said latter fork are the yarn guides 7 hereinbefore referred to, these guides being pivotally mounted upon a stud or pin 11 extending transversely of the recess between said arms. The yarn guides 7 are all substantially similar in construction and comprise forwardly extending curved arms 12 provided at their extremities with suitable perforations 13 for

guiding the yarn to the needles. When in their normal yarn-guiding positions, said arms 12 are arranged to rest within a slot 14, generally termed the throat, of the latch ring 7, and against a transversely arranged supporting or throat plate 15, and in this position said yarn guides are adapted to be maintained by suitable springs 16, herein shown as connected at one end with a transversely disposed bar 17, and at their opposite ends with extensions 18 upon the said yarn guides 7. By reason of the springs 16 acting constantly upon said yarn guides, said yarn guides will be self-acting in their movement from their inoperative to their yarn feeding positions, as is characteristic of the more recent stocking knitting machine. The yarn guides are moved in a reverse direction,—that is, from their operative or yarn feeding positions to their inoperative positions by automatic pattern-controlled means, herein consisting of longitudinally movable or sliding thrust bars 19—19 arranged to be moved in ways 20, 21 disposed adjacent the upper and lower ends respectively of said thrust bars upon fixed portions of the machine frame. For instance, the ways 20 are mounted upon lugs 22 carried by the standard 9, while the ways 21 are supported by a suitable laterally projecting stud or rod 23 secured to the base of the knitting machine, not shown. The upper ends of the bars 19 are operatively connected with their respective yarn guides preferably by means of links 24, each of which is pivotally connected at 25 to the upper end of one of the bars 19, while the opposite end is connected with the end of the extension 18 of the yarn guide and maintained in such relation by a pivot pin 26 which enters, in the present example, an elongated slot 27, said slot being provided preferably, though not essentially, for the purpose of permitting an independent action of the yarn guide in one direction under the impulse of its spring 16, thus allowing said yarn guide upon the retraction of the thrust bar 19 to be moved by its spring to its lower or yarn feeding position. The thrust bars 19 are caused to slide within their ways 20, 21 by suitable elevations 28 upon the face of a cylindrical revoluble cam or pattern means 29 mounted upon a suitable shaft 30, motion being imparted to said cam by any suitable driving means, such as gears 31, 32. In view of the fact that the several yarn guides 7 and their operatively connected thrust bars 19 are operated in substantially the same manner, but at different periods, a description of one complete yarn changing unit will, it is believed, be sufficient. Assuming that the pattern means, which includes the cam 29, is revolving in the direction of the arrow *a* (see Fig. 2), the engagement of the cams 28 with their respective thrust bars 19

will force said bars upwardly in the ways 20 and 21, and in doing so the link 24 will be drawn upwardly from the position shown in full lines (Fig. 5) to that shown in dotted lines in said figure. Previous to the upward movement of said thrust bar, said link 24 rests substantially in a position with the pin 26 at the left extremity of the slot 27, and as there is no play between the link and the parts connected therewith other than the slot 27, the upward movement of the thrust bar 19 will immediately begin to move the yarn guide 7 attached thereto through the extension 18, thereby extending the spring 16 and causing said yarn guide to move to the upper dotted position shown in Fig. 5, thus withdrawing the yarn from the needles and holding the same in an inactive position in readiness to again be led to the needles upon the release of the yarn guide by the elevation 28 of the cam 29 when said elevation is moved from under the lower end of the thrust bar 19. When this latter action takes place, the spring 16, acting at all times upon said yarn guide, will cause the same to drop to its lower or full line position and again present the yarn to the needles. It is desirable in machines of the character described that the yarn guides be mounted upon their latch ring or supporting member in such a way as to be moved bodily with said supporting member when the same is raised for the topping or transferring operation, and it is for this purpose that the latch ring is pivoted at 8. It is also desirable that no unnecessary movement be imparted to the yarn guide 7 during such bodily movement or during the swinging of said latch ring from its operative to its inoperative position. By referring to Figs. 2, 5 and 6, it will be seen that the axis of the pivoted pin 26, when the yarn guide 7 is in its lowermost position, is substantially coincident with the axis of the pivot for said latch ring, and obviously, with the parts shown in Fig. 2, any movement of the latch ring 6 about its axis may be effected without causing the yarn guides 7 to be moved about their axis.

Should the yarn guides be in their upper or dotted line position, the axis of the pivot 26 will not be coincident with the axis of the pivot 8, but upon movement of the latch ring to its upper position, the toggle consisting of the link 24 and extension 18 will be straightened or partially straightened by the action of the spring 16, and will permit said yarn guide to assume a position with the yarn guiding end thereof against the throat plate 15; in fact, all of the yarn guides will assume this position when said latch ring is in its elevated position, regardless of the position of the thrust bar attached thereto. Upon returning said latch ring to its lowermost or operative position,

the yarn guides connected with the elevated thrust bars will automatically assume their elevated positions in readiness to continue the knitting from the point where knitting was stopped by the raising of said latch ring.

In Fig. 3, I have illustrated a yarn guide and actuating means therefor similar to those illustrated in Figs. 1, 2, 4, 5 and 6 inclusive, but in this case the yarn guide 7 is connected directly with the thrust bar 19 by means of a link 60, which is not provided with a slot 27 as shown in the previous forms, and thus prevents the yarn guide 7 from being moved independently of its thrust bar. In this form the movement of said yarn guide 7 is always in cooperation with the thrust bar 19, never independent thereof, consequently the spring 16, which normally tends to maintain said yarn guide in its lower yarn knitting position, will also tend to restore the thrust bar 19 to its lowermost position when the elevation 28 is removed from beneath the end thereof.

In the embodiment of my invention illustrated in Fig. 7, I have shown a yarn guide 35 mounted upon a supporting member, in the present instance a latch ring 36. The inner or active end 37 of said guide normally lies within the slot or throat 38 of said ring and adjacent the lower edge of said ring as illustrated in full lines in Fig. 7. The yarn guide 35 is pivotally connected with said latch ring by a pin 39 extending transversely of the yoke 40 and between the arms of the fork 41. The pin 39 is arranged to engage the said yarn guide within a slot 42 formed in an extension 43 of the yarn guide, which extension is arranged upon opposite sides of the pivot 39 from the active or yarn guiding end 37 thereof. The yarn guide 35 is normally maintained with the pin 39 at the right hand end of said slot 42 by means of a spring 44, one end of which is attached to said yarn guide and the opposite end to a pin 45 extending across the gap between the arms of the fork 41 and constituting the pivot for said latch ring. The spring 44 is adapted to exert a constant tension upon the yarn guide 35 to maintain it in its yarn feeding position, as shown in full lines in said Fig. 7, and means are provided to move said yarn guide in opposition to the action of said spring to its inactive or inoperative position, said means preferably consisting of a thrust bar 46 mounted in a similar manner to the thrust bar 19, previously described, said thrust bar 46 being arranged in ways 47. The upper end of said thrust bar is operatively connected with the yarn guide 35, herein by means of a pin 48, and engages said yarn guide within a slot 49 disposed as herein shown at an angle to the slot 42 and extending toward the free end 37 of said

yarn guide. This slot has two functions, one of which is to permit a limited movement of the pin 48 therein during the vertical reciprocations of the thrust bar 46 in moving said yarn guide from its operative 70 to its inoperative position, said spring 44 preventing, during such movements, any relative sliding movement between said yarn guide and the pin 39. The other function of said slot is to provide for movement of the 75 yarn guide longitudinally to the rear of its yarn feeding position during the upward swinging movement of the latch ring 36 for transferring, etc. During this movement of said latch ring, the pin 39 will 80 travel toward the left in said slot 42 until the same occupies a position at the opposite or left hand end of said slot, at which time said yarn guide will be moved bodily toward the left in said figure and until the 85 pin 48 occupies a position at the right hand end of the slot 49, and when in said positions said yarn guide and the pins 39 and 48 will serve as stops for the latch ring and prevent the same from being moved too 90 far in its swinging movement.

It will be observed that the thrust bar 46 is shown in its lowermost position in full lines in Fig. 7, but should the same be in its elevated position, as illustrated in dotted 95 lines, and the latch ring be moved to its inoperative position, the result will be practically the same as hereinbefore described, except as to the slight variation between the two positions of the pin 48 as shown down, and that occupied by said pin when the thrust bar is raised. In either event, the 100 yarn guiding end of the yarn guide will be raised to a substantial distance above its normal yarn guiding position, and remain 105 in a convenient place whereby threading of the same may be effected without difficulty and without interference from the needles or from the latch ring, which at this time will be in its rearmost position.

In the above-mentioned arrangement where the latch ring is capable of being moved to its upper and rear position without imparting an equal bodily movement to the 110 yarn guides, it is necessary to omit the throat plate generally employed in knitting machines of this character and, as shown at 15 in Fig. 5, to allow for said swinging movement of the latch ring. It is, however, necessary where latch needles are employed, to 115 provide such a throat plate in order properly to guide the yarn from the various yarn guides to the needles. This is particularly true where several yarn guides are employed and where to and fro knitting is to be produced, as the ends of the yarn guides have to be far enough removed from the needle cylinder to clear the latches of the needle should the same swing outwardly during 120 such reciprocation, as they are very likely 125 130

to do. Therefore, for this purpose a throat plate 38^a is mounted independently of the latch ring and upon a plate 38^b within which are formed ways 47 for the thrust bars 46. This throat plate is provided with the usual recessed portion 38^c, through which the yarns pass to the needles of the machine, not shown in the drawings. By this arrangement said throat plate will always remain stationary, 10 while the latch ring may, when in its normal operating position, rest thereon as a support.

In Fig. 8, I have shown still another type of yarn guide, wherein the latch ring or supporting member for the yarn guide is substantially the same as in the previous examples, and upon said ring the yarn guide 50 is pivotally mounted at 51 upon a stud extending transversely of the gap or recess between the arms of the fork 44 of the latch 20 ring. The yarn guide 50 is provided with a downwardly extending curved arm 52 which has at its forward end a suitable perforation 53 through which the yarn is led to the needles of the knitting machine. A spring 54 is attached to said yarn guide and tends normally to rock said yarn guide about the axis of the pivot 51 toward its yarn feeding position as shown in full lines. The movement of said yarn guide is limited in this 30 direction by the thrust bar 55, which is operatively connected with said yarn guide by means of a pin 56 and rests at its lower end in the usual manner against the periphery of the drum 29 (see Fig. 2), thus stopping the 35 yarn feeding end 53 of the yarn guide in the correct position for feeding the yarn to the needles. The operation of said yarn guide 50 from its operative position to its inoperative position is effected in substantially the same manner as are the yarn guides previously described, that is, by the upward movement of the thrust bar 55 while in engagement with its elevation 28 on said 40 cylindrical drum 29. It is desirable in this 45 example, as in the previous cases, that the latch ring be permitted to swing to its upper or idle position particularly to enable the work to be transferred. In order to allow for such a movement of said latch ring, the 50 yarn guide 50 is extended at 56 in curved formation, and is provided with a segmental slot 57 which describes an arc, the axis whereof may be and preferably is coincident with the axis of said latch ring when the 55 yarn guide is in its lowermost position, and obviously by reason of said segmental slot 60 the pin 51, which is the fulcrum on which said yarn guide swings when moved to its uppermost or dotted position, will be moved longitudinally of said slot 57 to the outer extreme end thereof, and during said swinging movement no movement of said yarn guide will take place provided the same is 65 in its lower yarn feeding or full line position. Should said yarn guide be raised to

its inoperative position, it will be evident that a slight swinging movement of said yarn guide will take place about the axis of the pivot 56 during the movement of the pin 51 along said segmental slot. The pin 56 is 70 arranged to engage the yarn guide 50 within a somewhat elongated hole 58 in order to allow for any angular movement of said thrust bar 55 during its yarn guide elevating operation. 75

A throat plate 55^a is provided beneath said latch ring and is for the same purpose and functions in the same manner as does the throat plate 38^a, referred to in connection with the example illustrated in Fig. 7. 80

In Fig. 9, I have illustrated a different type of thrust bar from that illustrated in the previous forms. In this example, the upper end of the thrust bar 61 is arranged in suitable ways 62, and has its upper end rounded at 63 to engage the under edge 64 of a yarn guide 65 pivoted at 66 within the slot of the latch ring 6. A spring 67 attached at one end to said yarn guide and at the other end to the pivot 68 for said latch 90 ring, normally tends to maintain said yarn guide in its lowermost or yarn feeding position against the throat plate 15. Means are provided to raise the thrust bar 61, and thereby move said yarn guide 65 from its operative to inoperative position, said means consisting of the usual pattern means or pattern drum 29 having the usual elevations 28 thereon, and these elevations are arranged to engage a cam lever 69 pivoted at 70 to a fixed portion of the machine, not shown. This cam lever has pivotal engagement at 71 with the lower end of the thrust bar 61, and obviously any pivotal movement of said cam lever 69 will transmit 95 an equivalent movement to the thrust bar 61 to actuate the yarn guide operatively associated therewith. 100

While I have herein shown and described merely for illustrative purposes one specific embodiment of my invention, and have disclosed and discussed in detail the construction and arrangement incidental to such disclosure, it is to be distinctly understood that the invention is limited neither to the mere details or relative arrangement of the parts of the yarn knitting mechanism nor to the specific application herein shown, but that extensive variations from the illustrations 110 may be made without departing from the principles thereof. 115

I claim:

1. In a knitting machine a pivoted yarn guide, a pivoted yarn guide support and means including a movable bar operatively linked with said yarn guide to move the same to and from yarn feeding position, said link connection permitting pivotal movements of said support without moving said movable bar. 125 130

2. In a knitting machine the combination of a pivoted yarn guide support, a yarn guide pivoted on said support, a thrust bar pivotally connected with said yarn guide so as to permit independent movement of said yarn guide with its support relatively to said thrust bar and pattern means for imparting movement to said thrust bar.
3. In a knitting machine, the combination of a pivoted latch ring, a yarn guide mounted in said latch ring, a revoluble cam, and means attached to said yarn guide and adapted to cooperate with said cam to effect movement of said yarn guide into and out of its yarn feeding position said means permitting independent movement of said latch ring with said yarn guide to and from knitting position.
4. In a knitting machine, the combination of a swinging latch ring, a yarn guide mounted in said latch ring, a revoluble cam, and means attached to said yarn guide and adapted to cooperate with said cam to effect movement of said yarn guide into and out of its yarn feeding position, said means permitting independent movement of said latch ring with said yarn guide to and from knitting position.
5. In a knitting machine, the combination of a revoluble needle carrier, a non-revoluble pivoted latch ring, a plurality of yarn guides pivotally mounted in said latch ring and movable bodily therewith, a thrust-bar pivotally connected with each of said yarn guides adapted to permit independent movement of said latch ring with said yarn guides to and from knitting position, and pattern means to impart movement to said thrust bars to move said yarn guides from one position to another.
6. In a knitting machine, the combination of a swinging latch ring, a yarn guide pivoted in said latch ring, pattern means, a thrust-bar operated by said pattern means, and means pivotally connecting said yarn guide and said thrust-bar adapted to effect cooperation therebetween and to allow said yarn guide to swing bodily with said latch ring without moving said thrust-bar.
7. In a knitting machine, the combination of a swinging latch ring, a yarn guide pivoted in said latch ring, pattern means, a thrust-bar operated by said pattern means, and means interposed between said yarn guide and said thrust-bar adapted to effect cooperation therebetween and to allow said yarn guide to swing bodily with said latch ring without movement of said thrust-bar or pivotal movement of said yarn guide.
8. In a knitting machine, the combination of a swinging latch ring, a yarn guide pivoted in said latch ring, pattern means a thrust-bar operated by said pattern means, and a link interposed between said thrust-bar and said yarn guide, said link having limited 60 65 70 75 80 85 90 95 100 105 110 115 120 125 130 135 140 145 150 155 160 165 170 175 180 185 190 195 200 205 210 215 220 225 230 235 240 245
